UNITED STATES PATENT OFFICE.

HUBERT A. MYERS, OF TOLEDO, OHIO, ASSIGNOR TO THE MYERS REGULATOR COMPANY, OF TOLEDO, OHIO, A CORPORATION OF OHIO.

WINDOW-REGULATOR SUPPORTING PLATE.

Application filed October 27, 1926. Serial No. 144,463.

My invention has for its object to provide an efficient window-regulator supporting plate whereon the regulator operating parts may be secured and thus the regulator may 5 be installed as a unit in an automobile frame. The invention is applicable to different forms of regulators but is particularly applicable to the type of regulators having a sector rack and a pinion and a means for 10 operatively connecting the rack to the window for raising and lowering the window. The invention provides a chamber produced by forming a boss in the sheet metal, of which the supporting plate is formed, and 15 a pinion is located in the chamber. In the form of construction shown, the sector is made in the form of an arcuate strip and is pivotally mounted so as to pass through slots formed in the boss and engage the 20 pinion whereby the pinion will be maintained in its engaging relation, notwithstanding the flexure of the plate that may occur in operating the crank handle, which is commonly used for raising and lowering 25 windows. This engaging relation between the sector and the pinion will be maintained for the reason that the metal about the pinion and the portion of the arcuate sector strip within the chamber cannot be 30 flexed by an unusual force that may be applied in the use of the device.

Also the invention provides a means for preventing localized bending of the window counter-balancing spring that is usually convolute in form and connected directly, or indirectly, to the rack and the plate. The invention also provides a convolute spring particularly applicable to the type of window regulators described.

40 The invention may be contained in window regulators of different forms and to illustrate a practical application of the invention, I have selected a window regulator embodying the invention as an example 45 of such constructions and shall describe it hereinafter. The form of structure selected is shown in the accompanying drawing.

50 Fig. 1 of the drawing illustrates the window regulator in position for operating the window. Fig. 2 illustrates a side view of the regulator, part being shown has broken away in order that the convolute spring may be shown. Fig. 3 is an edge view of the window regulator shown in Fig. 2. Fig. 4 il-

lustrates a boss formed by striking up the 55 sheet metal of the supporting plate. Fig. 5 is a view of a section taken of the plane of the line 5—5 indicated in Fig. 4. Fig. 6 is a view of a section taken on the plane of the line 6—6 indicated in Fig. 5. Fig. 7 60 is a view of a cross-section of the counter-balancing spring used for counter-balancing the weight of the window.

The supporting plate 1, selected as an example of embodiments of my invention, is 65 formed from sheet metal and is provided with a boss 2 that is formed from the sheet metal. It has a flange 3 for pivotally supporting the sector 4.

The sector 4 is in the form of an arcuate 70 strip having the teeth 5 on its outer edge. The ends of the sector 4 are connected to the arm 6 by means of suitable rivets such as the rivet 7. The arm 6 is provided with a suitable opening that substantially fits the 75 flange 3. When therefore the arm and the sector are supported in position on the boss 2 the outer edge of the flange 3 is flared so as to pivotally secure the sector and the arm in position. When the edge of the flange 80 has been flared the boss 2 forms a lateral bearing of broad area and also a pivot of considerable area for pivotally supporting the sector and the arm in a plane parallel to the plane of the body portion of the plate 85 and in spaced relation therewith.

The convolute spring 8 is connected at one end to the sector through the arm 6, the end of the spring may be provided with a hook that may be so placed as to engage 90 the pin 9. The other end of the spring is turned toward its axis and is anchored in a slot 10 formed in the side of the boss 2. The spring 8 is drawn sufficiently taut to carry all of, or a substantial part of, the 95 weight of the window and thus the spring counter-balances to a greater or less extent the weight of the window.

The width of the strip from which the spring is formed is substantially the 100 height of the boss 2 except for the flange 3 and thus the boss spaces the arm 6 from the plate 1 a distance that is substantially the width of the spring.

Owing to the fact that the spring is convolute in form, the inner end portion ordinarily introduces a means that causes a bending of the spring in its use that de-

parts from its normal convolute curve. These marked changes in direction in the continuous use of the spring is thus localized and invariably causes the spring to break at this point. In order to obviate the localized bending of the spring the boss 2 has a lateral surface 11 that is also convolute in form, the ends of the surface 11 being joined by a plane surface 12 having a length substantially the same as the thickness of the strip from which the convolute spring is formed. The slot 10, in which the inner end of the spring is inserted to anchor the spring, is located in proximity to the surface 12 and consequently the end of the first convolute portion of the spring, will, if it is drawn down against the boss, be located on the surface 11 and on the surface of that portion of the spring where it is anchored to the boss without being deflected from a normal convolute curve produced in its distortion from its normal condition, either in placing the spring so as to counter-balance the window, or when the window is raised and lowered in the use of the regulator.

In the manufacture of window regulators, it is desirable to use as light stock as possible conducive to efficient results. By my invention the sheet metal plate may be formed from sheet metal that is lighter than is ordinarily used in such constructions. In the use of light stock, there is always the possibility that upon extreme pressure of the actuating part of the window regulator, the plate will bend which ordinarily will disengage the pinion from the sector. In order to prevent the flexure of the plate, that may be produced by any cause, from displacing the teeth of the sector relative to the pinion, or vice versa, I form a raised portion, or boss 15, in the upper part of the plate 1 in which is located the pinion 16. The sector 4 being made in the form of a strip, I provide slots 17 and the sector is located in the slots 17. It extends through the chamber within the boss and engages the pinion within the chamber. Since the metal of the boss 15 completely surrounds the pinion, and also surrounds that portion of the sector that engages the pinion, any amount of flexure of the plate will not cause disengagement of the teeth of the pinion and the sector. Also since the sector is in the form of a strip that is secured only at its ends with the supporting part of the sector, a complete semi-circular sweep may be given to the sector and produce ample opportunity for the manipulation of the window, while the teeth of the strip is held in engaging relation with the teeth of the pinion by the sector passing through slots formed in the sheet metal plate.

The pinion 16 may be operated by the

usual crank handle 20 which is connected to a shaft 21 of the pinion whereby the sector strip 4 is moved and, through the operation of the arm 6, the window is raised or lowered according to the direction in which the crank handle 20 is rotated.

I claim:

1. In a supporting plate for window regulators, a sector, a convolute spring, means for connecting the spring to the sector, the plate having a boss struck up from and formed integral with the plate and having a means for anchoring the spring, the sector pivotally supported on the boss, the boss forming a broad lateral bearing surface for the sector. 75

2. In a supporting plate for window regulators, a sector, a convolute spring, means for connecting the spring to the sector, a boss having a means for anchoring the spring and having a surface corresponding to the innermost convolution of the spring. 85

3. In a supporting plate for window regulators, a sector strip, a pinion for operating the sector strip, an arm secured to the ends of the sector strip, the strip located between the arm and the plate, the plate having a boss struck up from and formed integral with the plate and having a flaring flange for pivotally connecting the arm to the plate and forming a broad lateral bearing for the sector. 90

4. In a supporting plate for window regulators, a sector strip, a pinion for operating the sector strip, an arm secured to the ends of the sector strip, the strip located between the arm and the plate, the plate having a boss struck up from and formed integral with the plate and having a flaring flange for pivotally connecting the arm to the plate and forming a broad lateral bearing for the sector, a convolute spring connected to the arm and surrounding the boss. 100

5. In a supporting plate for window regulators, a sector, an arm connected to the sector, the plate having a boss struck up from and formed integral with the plate and protruding from the plate for pivotally supporting the arm and sector in spaced relation with respect to the plate and forming a broad lateral bearing for the said sector and arm, a convolute spring connected at one end to the arm, the boss having means for anchoring the other end of the spring. 110

6. In a supporting plate for window regulators, a sector, an arm connected to the sector, a boss protruding from the plate for pivotally supporting the arm and sector in spaced relation with respect to the plate and forming a broad lateral bearing for the said sector and arm, a convolute spring connected at one end to the arm, the boss having a lateral surface corresponding to the innermost convolution of the spring and having means for anchoring the inner end of the spring. 120

7. In a window regulator, a supporting plate having a recess and pinion located in the recess, a sector strip extending through the plate and the recess, a convolute spring, 5 means for connecting the spring to the sector, a boss having a means for anchoring the spring and having a surface corresponding to the innermost convolution of the spring.
8. In a window regulator, a supporting 10 plate, a boss struck up from the supporting plate and integrally formed therewith, the boss having a tubular end portion of a diameter smaller than the diameter of the boss, a convolute spring, the boss having a slot for 15 receiving one end of the convolute spring, a segmental gear rotatably supported on the end portion of the boss having the smaller diameter and connected to the remaining end of the convolute spring.
9. In a window regulator, a supporting 20 plate, a boss having an exterior convolute surface, a slot formed in the boss at that portion of the surface having the smaller radius, a convolute spring having one end engaging 25 in the slot of the boss, a segmental gear pivotally supported on the plate and connected to the remaining end of the spring.
10. In a window regulator, a supporting 30 plate, a boss having an exterior convolute surface, a slot formed in the boss at that portion of the surface having the smaller radius, a convolute spring having one end engaging 35 in the slot of the boss, a segmental gear pivotally supported on the end wall of the boss and connected to the remaining end of the
- convolute spring, the spring being located between the sector arm and the plate.
11. In a window regulator, a supporting plate, a pinion rotatably supported on the supporting plate, an arm in operative connection with the window for raising and lowering the window and rotatably supported on the supporting plate, a sector connected at its ends to the arm and operated by the pinion, the sector located between the 40 arm and the supporting plate, a convolute spring located between the arm and the supporting plate, and connected to the supporting plate and located substantially in the plane of the sector and the pinion, and means 45 for connecting the spring to the arm.
12. In a window regulator, a supporting plate, a pinion rotatably supported on the supporting plate, an arm in operative connection with the window for raising and 50 lowering the window, a sector connected at its ends to the arm and operated by the pinion, the sector located between the arm and the supporting plate, a boss located on the supporting plate for rotatably supporting the arm and the sector, a convolute spring located between the arm and the supporting plate and connected to the boss and substantially in the plane of the sector and the pinion, and means for connecting the 55 spring to the sector.

In testimony whereof I have hereunto signed my name to this specification.

HUBERT A. MYERS.
